US0D1113716S

(12) **United States Design Patent** (10) Patent No.: **US D1,113,716 S**
(45) Date of Patent: ** Feb. 17, 2026

(54) **THERMOMETER CHARGING CASE**

(71) Applicant: **SHENZHEN QIANFENYI
INTELLIGENT TECHNOLOGY
CO., LTD**, Shenzhen (CN)

(72) Inventors: **Yang Liu**, Shenzhen (CN); **Ziyu Zhan**, Shenzhen (CN); **Yanxin Huang**, Shenzhen (CN)

(**) Term: **15 Years**

(21) Appl. No.: **35/521,103**

(22) Filed: **Apr. 19, 2024**

(80) **Hague Agreement Data**

Int. Filing Date: **Apr. 19, 2024**

Int. Reg. No.: **DM/237212**

Int. Reg. Date: **Apr. 19, 2024**

Int. Reg. Pub. Date: **May 31, 2024**

(30) **Foreign Application Priority Data**

Dec. 20, 2023 (CN) 202330840163.0

(51) **LOC (15) Cl.** **13-02**

(52) **U.S. Cl.**

USPC **D13/108**

Primary Examiner — Amanda Christensen

(57) **CLAIM**

The ornamental design for a thermometer charging case as shown and described.

DESCRIPTION

1. Thermometer charging case

1.1: Front view;

1.2: Back view;

1.3: Left view;

1.4: Right view;

1.5: Top view;

1.6: Bottom view;

1.7: Perspective view;

1.8: Perspective view.

The broken lines depict portions of the thermometer charging case that form no part of the claimed design.

1 Claim, 8 Drawing Sheets
